UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A NAPPY.

48,529.

Specification for Design.

Patented Feb. 8, 1916.

Application filed December 15, 1914. Serial No. 877,453. Term of patent 14 years.

To all whom it may concern:

Be it known that I, ANDREW J. SANFORD, a citizen of the United States, residing at Newark, Ohio, have invented a new, ornamental, and original Design for a Nappy, of which the following is a specification, reference being had to the accompanying drawing, forming part thereof.

Figure 1 is a side elevation of a nappy embodying my new design; Fig. 2 is a bottom plan view; Fig. 3 is a fragmentary vertical section of the nappy, and Fig. 4 is a vertical section of the same.

I claim:

The ornamental design for a nappy, substantially as shown.

ANDREW J. SANFORD.

Witnesses:

J. P. GOODWIN,
MYRTLE E. GORBY.
